(57) **CLAIM**

The ornamental design for a RC robot toy and controller set, as shown and described.

DESCRIPTION

FIG. 1 is a perspective view of the RC robot toy and controller set showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the remote-control device for the RC robot toy and controller set;

FIG. 10 is a perspective view thereof from another angle of the remote-control device for the RC robot toy and controller set;

FIG. 11 is a front elevational view from the remote-control device for the RC robot toy and controller set;

FIG. 12 is a rear elevational view from the remote-control device for the RC robot toy and controller set;

FIG. 13 is a left side elevational view from the remote-control device for the RC robot toy and controller set;

FIG. 14 is a right side elevational view from the remote-control device for the RC robot toy and controller set;

FIG. 15 is a top plan view from the remote-control device for the RC robot toy and controller set;

FIG. 16 is a bottom plan view from the remote-control device for the RC robot toy and controller set; and,

FIG. 17 is an enlarged view of the portion indicated with the number 17 in FIG. 1.

The broken lines shown in the drawings represent portions of the RC robot toy and controller set that form no part of the claimed design.

1 Claim, 17 Drawing Sheets
